UNITED STATES PATENT OFFICE

FRANCIS W. MCFARLAND, OF MARTINEZ, CALIFORNIA

FREIGHT CAR LOCK AND SEAL

Application filed March 10, 1930. Serial No. 434,588.

The invention is for a freight car lock, and has special reference to the locking of freight cars in replacement of present sealing methods.

The present system of locking freight cars consists of the use of lead-wire seals and self locking seals, which can readily be removed by cutting or breaking the wire or metal strip.

The object of the present invention is to provide a lock to replace the present seal, which can be opened with a key of standard use similar to the ordinary switch key, but only in cooperation with specially designed metal slugs, thereby preventing unauthorized persons from gaining access to a locked car.

Another object of the invention is to provide a lock of universal application, and a cooperating slug of special construction and provided with identifying markings.

A further object of the invention is to provide an efficient lock which can not readily be tampered with, and which can be locked without the use of a slug or key, but which requires the use of both slug and key for unlocking.

Other objects of the invention will become apparent as the following description is read in conjunction with the drawings and from the appended claims.

The invention consists primarily of a ratchet type of lock comprising two members attached respectively to the door and door frame or car body. One of the members comprises a mounting member, and a pivoted spanning latch, with arcuately formed serrated periphery adapted to engage a cooperating serrated pawl in the second member. The second member comprises a housing with a recess for admission of the arcuate end of the latch and for enclosure of the locking mechanism which consists of a serrated pawl pivoted in said housing, a spring to cause the pawl to engage the latch, a tumbler operated by a key, a recess or slot for admission of a slug and a chamber for reception of the slugs after operation of the lock, the chamber being locked by special locking means, the tumbler and pawl being so related that when a slug is inserted a key operating on the tumbler causes interposed coaction between the tum-

bler and pawl with the slug, the slug dropping into the chamber after releasing the pawl and coincidentally the latch.

Similar reference characters are used to designate similar parts throughout the several views.

Referring to the accompanying drawings:

Fig. 1 is a side elevation of a freight car indicating my invention applied thereto;

Fig. 2 is a sectional plan view taken on line 2—2 of Fig. 3;

Fig. 3 is a sectional elevation taken on line 3—3 of Fig. 2;

Fig. 4 indicates an elevation and cross section respectively of a proposed slug;

Fig. 5 is a top plan view of the invention as applied to a car;

Fig. 6 is a fragmentary view of a car with a front elevation of my invention.

A box car Fig. 1 is provided with the customary door 8 and jamb 9. A bracket 10 is bolted to the jamb or car side 9 through bolt holes 12 by means of bolts 13 and has an aperture 14 therethrough for reception of the latch 15 which is pivoted therein by means of a bolt or rivet 16.

The latch 15 is formed to U shape with one leg pivoted as at 16, the periphery of the opposite leg 22 being arcuately formed to a center at the pivot 16, and being provided with engaging teeth 17.

A housing 18 is adapted to be attached to a car door 8 through holes 19 by means of bolts 20. The housing 18 is provided with integral front, rear, end and top walls, being open at the bottom and having part of one end wall removed as at 21 for reception of the latch 15. A pawl 23 is pivotally mounted at 24 between the front and back walls of housing 18 and is provided with cooperating engaging teeth 17, a spring 25 cooperating at 26 to force the pawl teeth into engagement with the ratchet teeth.

A tumbler 27 is pivoted at 28 between the front and back walls of the housing and is provided with a heel 29 restricting the counterclockwise movement thereof, the clockwise movement being restricted by the shoulder 30. A key pin 31 is adapted to cooperate with the hollow key shank of a switch

key. Projections 32 are provided in the slug slot 33, the slug slot being narrower than the enclosing recess for the operating mechanism and continuing downward between the pawl 23 and tumbler 27 as indicated at 34. A heel 35 prevents tampering with pawl 23 with unrelated means. The chamber is closed at the bottom by a door 36 pivotally related to the housing at 37 and having a wall 38 for retention of the slugs 39 and provided with means at the outer end for locking the door as at 40. A slot 41 is provided for sighting the slugs 39 deposited in the receptacle on the door 36. A key hole 42 is adapted to cooperate with the well known switch key.

The slugs are preferably formed in the shape of circular discs having grooves 43 adapted to cooperate with the projections 32 on entering the slot 33 and have identifying marks including the initials of the issuing railroad 44, the issuing station number 45 and a serial number 46. Other identifying marks could be supplied on the opposite side if desired.

25 The operation of the invention is as follows. With the car door in closed position, the latch 15 is swung counterclockwise to its limit of travel, as indicated in Fig. 3, the pawl 23 automatically engaging and retaining the latch. When it is desired to open the lock, it is first necessary to drop a slug in the slot 33, which rolls to the position indicated in Fig. 3 at 47. A key is inserted in the keyhole 42 and turned in a clockwise direction, engaging the lower surface of tumbler 27 and moving it about the pivot 28 and coincidentally forcing the slug against and moving the pawl 23 in a counterclockwise direction releasing the latch 15 and permitting it to swing out 30 of the housing 18. As the tumbler is swung back, the slug passes between pawl 23 and surface 48 of tumbler 27 and drops into the receptacle as indicated at 39. A special lock is provided for locking the door 36, keys being provided only to persons authorized to remove and record the slugs.

When a seal is removed from a car, a record of the seal can readily be omitted whereby there is no method of determining where the car was opened. With the lock which is the subject of this application, the record is provided when the car is opened.

Having described an operative method of constructing and operating the device, it will be understood that variations in design, construction and arrangement of parts which are consistent with the spirit of the appended claims may be resorted to without detracting from the scope or advantages of the invention.

I am aware that locks have been made for freight cars, therefore I do not claim such combination broadly, but I do claim:

1. A lock for freight cars comprising a bracket, a substantially U shaped latch, one

leg of which is pivotally related to said bracket attached to the side of a car, the other leg thereof having an arcuately formed periphery centralized at the pivot and provided with ratchet type engaging teeth, a cooperating lock into which said other leg is adapted to be inserted, an engaging pawl adapted to engage said latch teeth, and releasing mechanism for said latch consisting of a pivoted tumbler in spaced relation to said latch adapted to normally retain a freely inserted slug in cooperative relation to said latch and adapted to release said latch by combined cooperation of a key and inserted slug, the slug being released following release of said latch.

2. A lock for car doors, a latch and a lock in cooperating relation, said latch comprising a bracket with pivotally related U shaped latch member, one leg being pivoted to said bracket, the other leg being arcuately formed with said pivot as a center and having ratchet teeth formed on the periphery thereof, said lock comprising a housing adapted to receive said latch, a pawl adapted to engage said latch, a tumbler spacedly related to said pawl, a slot having selective projections, a slug adapted to pass through said slot and clear said projections, said slug being retained between said pawl and said tumbler whereby movement of said tumbler by means of a key is transmitted through said interposed slug to said pawl for disengaging said pawl from said latch, said slug thereupon being deposited in a receptacle by gravitational influence.

3. In combination, a bracket, a U shaped latch having engaging teeth formed in an arcuately formed periphery of one leg, the other leg being pivoted to said bracket, a housing, said one leg being insertable in said housing, a pivotally mounted resiliently urged engaging element adapted to cooperate with said one leg, a slug slot and passageway in said housing, a tumbler pivotally mounted in spaced relation to said engaging element and adapted to retain a slug deposited in said passageway in cooperative relation to said engaging element, said tumbler being adapted for cooperation with a key for releasing said engaging element.

In testimony whereof I have affixed my signature.

FRANCIS W. McFARLAND.
